UNITED STATES PATENT OFFICE.

JOHN B. THOMAS, OF LAKewood, NEW JERSEY.

RAILWAY-BED AND RAIL-SUPPORT.

1,109,267.

Specification of Letters Patent.

Patented Sept. 1, 1914.

Application filed March 21, 1912. Serial No. 685,146.

To all whom it may concern:

Be it known that I, JOHN B. THOMAS, a citizen of the United States, and a resident of Lakewood, county of Ocean, State of New Jersey, have invented a certain new and useful Improvement in Railway-Beds and Rail-Supports, of which the following is a specification.

My invention relates to railway beds and rail supports and has for one of its objects to construct a complete railway bed and rail support of reinforced concrete or like material in a single unit in which due allowance is made for expansion and contraction caused by changes of temperature in the atmosphere.

Another object of my improvement is to make it possible to remove and replace the railway rails without in the least disturbing the railway bed and rail supports.

Other objects of my invention will appear from the description hereinafter and the features of novelty will be pointed out in the appended claims.

Reference is to be had to the accompanying drawings in which—

Figure 1 is a perspective view of the improvement suspended in position ready to have the forms or molds placed in position to receive the concrete; Fig. 2 is a detail cross-section on an enlarged scale of a portion of the completed bed and support; Fig. 3 is a plan view of the same; Fig. 4 is a detail sectional view on the line 4—4 of Fig. 3; Fig. 5 is a horizontal section of one of the combined sole and fish plates; Fig. 6 is a similar view of one of the said plates used at the joint between two rail ends; and Fig. 7 is a view similar to Fig. 2 of a slightly different form of my invention.

In the drawings 10 are the rails which in the form of my invention shown in Figs. 1 and 2 each have their base resting upon a cushion 11 of wood or any other suitable material. These cushions 11 extend lengthwise throughout the length of the rails and preferably do not project beyond the longitudinal edges of the rail bases. At intervals throughout the length of the rails I provide fish plates 12 which are formed with integral portions 12^a adapted to engage the upper surface of the rail base and are further preferably formed with integral downwardly extending portions 12^b adapted to engage the edge of the rail base and the side of the cushions 11 and preferably con-

tinued to extend beneath and in contact with the lower surface of said cushion 11 to form sole plates 13. Fish plates 14 are located on the side of each rail web opposite to that on which the fish plates 12 are positioned so as to register therewith, and are provided with portions 14^a similar to the portions 12^a and also adapted to engage the upper surface of the rail base. The said fish plates 14 are also formed with downwardly projecting portions 14^b which engage the edge of the rail base and side of the cushion 11 in a manner similar to the portions 12^b, said portions 14^b being further provided with portions 14^c arranged to extend beneath and engage the lower surface of the sole plates 13. Bolts 15 extending through the fish plates and rail web and co-operating nuts 16 serve to properly secure the said fish plates and connected parts in operative position. Anchor rods 17, 18 extend respectively through suitable openings 13^a and 13^b in the sole plates 13 so as to depend therefrom and are provided with heads 17^a, 18^a seated in said openings and adapted to maintain said rods against movement in a downward direction. The upper surfaces of the heads 17^a—18^a in the assembled condition of the parts are preferably flush with the upper surfaces of the sole plates 13 and bear against the lower surface of the cushion 11 which thus prevents any movement of the rods 17, 18 in an upward direction. The openings in the sole plate preferably have an angular form and the rods 17, 18 are similarly formed in cross-section so that a rotative movement of the rods in the openings is prevented and the said rods are rigidly held in position. Each rod 17 and 18 has its lower end formed with a horizontal portion 17^b, 18^b for supporting the reinforcing bars 19, 20 which extend longitudinally beneath the rails 10. Cross-reinforcing bars 21, 22 are located at spaced intervals throughout the structure and are supported by the reinforcing bars 19, 20, hooks 21^a, 22^a on each bar 21—22 serving to prevent lateral displacement thereof relatively to the bars 19, 20. In actual use, I prefer to locate the rods 17, 18 in different planes and to position the bars 21, 22 in engagement therewith or in close proximity thereto so that the rods 17, 18, bars 19, 20 and cross-bars 21, 22 will be staggered relatively to each other. In order to facilitate the insertion of the anchor rods 17 through the open-

ings 13^a in the sole plate, I preferably provide openings 12^c in the portion 12^a and in alignment with the openings 13^a. After the parts so far described have been assembled 5 the structure will have the appearance illustrated in Fig. 1, it being understood that this structure is suitably supported on temporary supports of any convenient description to fix the same in the desired position, 10 and preferably with the reinforcing bars 20 and the ends 18^b of the anchor rods 18 at a distance from the ground. Forms of any suitable kinds are now placed lengthwise of each rail and parallel with the cross-reinforcing bars 21, 22 at a distance therefrom 15 to secure the intended results and the thickness of concrete desired in the finished road bed and rail support. These forms may be temporarily secured in any well known way, 20 after which concrete or any other coalescent material is poured into the same and permitted to set or harden. Owing to the fact that the bars 20 and the ends 18^b are located at a distance above the ground, this 25 concrete will flow beneath the same and a sufficient quantity is poured into the forms to completely surround the bars 20 and 22, as well as the bars 19 and 21. In the forms extending along the rails the concrete or 30 other material is introduced in sufficient quantity to extend to about the level of the upper surfaces of the cushions 11 and thus embedding the said anchor rods 17 and 18 in concrete throughout the greater portion of 35 their length. This concrete or other material after it has set thus forms parallel sleepers 23 which extend beneath the rails 10 and cross-braces 24 located at intervals and projecting from one sleeper 23 to the other, 40 both the sleepers and the cross-braces being reinforced by the bars 19, 20, 21 and 22 and the anchor rods 17 and 18 and forming a single, complete unitary railway bed and rail support on which the rails are firmly 45 secured and uniformly supported throughout.

In the form of my invention shown in Fig. 7 the cushions 11 are omitted and the rail base and sole plates 13 are in direct 50 contact with each other, this form being preferably in all other respects an exact duplicate of the form first described.

It will be seen that in both forms of my improvement all the work of bolting and assembling the rails, the cushions, the reinforcing bars and anchor rods is done, or may be done, before the concrete or other material is poured and preferably no work is performed on the bed or on the rails after 55 this pouring of the material has taken place. This method serves to secure the best results and is the most efficient manner of erecting concrete work, as it prevents injury to the said concrete which would occur if adjustments of the various parts were made after

the concrete had been poured. The cushions of wood or other material when used serve to take up or absorb the vibration induced by traffic over the rails or any other cause and prevent injury to the concrete or other 70 material from such causes, and when in position are protected against the effect of the elements on the bottom and two sides by the concrete or similar material and on the top by the base of the rails, thus assuring 75 said cushions a maximum life and period of usefulness. My improvement also provides a continuous and even support throughout the entire length and breadth of the rail base, a construction which will permit the 80 use of a rail much lighter in the web and base than the rails at present in use, yet giving the same efficiency as the present heavy rails. The life of the head of the rails will also be materially increased owing 85 to the fact that the rails are not constantly subjected to constant deflection between the ties as is the case with present structures. The anchor rods 18 in conjunction with the reinforcing bars 20 serve to prevent spreading 90 of the rails and take up all strains produced by a stress tending to tilt the rails away from each other. The anchor rods 17 and bars 19 act in a similar way to resist strains in the opposite direction, this being 95 due to the fact that the anchor rods 17 and 18 are located on opposite sides of a vertical plane drawn centrally through the rail web.

It will be seen that the combined fish 100 plate and sole plate shown in Fig. 6 is somewhat longer than the combined fish plate and sole plate illustrated in Fig. 5, the reason for this being that these fish and sole plates 12^a in addition to securing the parts 105 of the bed together are also intended to bridge the joints between two rails and to secure such rails together in alignment in the ordinary way. In order to permit a damaged or defective rail to be removed 110 and a new one substituted, I may provide recesses 25 in the sleepers 23 at the points where the fish plates on the inside surfaces 115 of the rails are located. The recesses 25 permit said fish plates to be moved away from the rails after the inside nuts 16 have been removed from the bolts 15, thus leaving the defective rail free to be removed 120 and another one substituted. The said recesses 25 are preferably formed during the molding of the bed and if desired may be lined with a metallic lining to prevent wear 125 if desired, and are preferably located on the inside of the rails as the heavy strains are in the opposite direction and will thus not tend to loosen the fish plates. If desired the ends 18^b of the anchor rods 18 may extend in the same direction as the ends 17^b of the rods 17 instead of in the opposite direction as illustrated in the drawings. The 130

position of the fish plates 12 and 14 may also be reversed if this is found advantageous; that is the fish plates 12 and their connected parts may be located on the inside of the rails and the fish plates 14 and connected parts may be placed on the outside of said rails instead of as shown.

If desired, the spaces between the braces 24 may be filled or partly filled with the 10 usual ballast or any other suitable material, or said spaces may be simply left free and, if found desirable, covered with a cover of any description. In some instances, it may be found advantageous to extend the bolts 15 15 from one rail to the other so as to bridge the space therebetween; it may also in cases of very heavy work sometimes be found advisable to make the sole plates and fish plates of a size so the same will be substantially continuous.

Various other changes in the specific forms shown and described may be made within the scope of the claims without departing from the spirit of my invention.

25 I claim:

1. In a railway road bed of the kind described, a unitary structure comprising the rails, depending means located beneath each rail, reinforcing means extending lengthwise beneath said rails and connected with said depending means, means connecting the reinforcing means together transversely and means for rigidly clamping said depending means and rails together.

35 2. In a railway road bed of the kind described, a unitary structure comprising the rails, a depending anchor rod located beneath each rail, a reinforcing rod extending lengthwise beneath each rail and connected 40 with an anchor rod, means connecting the reinforcing rods together transversely and means for rigidly clamping the anchor rods and rails together.

3. In a railway road bed of the kind described, a unitary structure comprising the rails, fish-plates arranged in pairs on opposite sides of each rail at intervals for clamping the rails, sole plates carried by said fish plates and extending beneath the rail base, 50 anchor rods detachably connected with said sole plates and depending therefrom, on opposite sides of vertical planes drawn through the rail webs, reinforcing bars beneath each rail and extending lengthwise 55 thereof and connected with said anchor rods and cross-reinforcing bars connected with said lengthwise extending reinforcing bars and bridging the space between said rails.

4. In a railway road bed of the kind described, a unitary structure comprising the rails, a cushion extending beneath and in

contact with each rail, a plate engaging the lower surface of each cushion, means for clamping said plates, cushions and rails together, reinforcing means extending 65 lengthwise beneath each rail, connections between said reinforcing means and said plates and means connecting said reinforcing means together transversely.

5. A railway road bed and rail support 70 comprising continuous parallel sleepers of coalescent material, integral cross-braces of similar material extending between said sleepers at intervals, rails supported on said sleepers, clamping plates engaging the rails 75 and having portions extending beneath the rail base and provided with openings, anchor rods extending through said openings and provided with heads seated therein and maintained against upward movement relatively to said plates by the rails, said anchor rods having their free portions embedded in the sleepers, reinforcing bars embedded in said sleepers and extending lengthwise throughout the same and connected with said anchor rods and cross-reinforcing bars embedded in said cross-braces 80 and extending lengthwise thereof from the reinforcing bars in one sleeper to the reinforcing bars in the other sleeper. 90

6. A railway road bed and rail support comprising continuous parallel sleepers of coalescent material, integral cross-braces of similar material extending between said sleepers at intervals, rails supported on said 95 sleepers, clamping plates engaging the rails and having portions extending beneath the rail base and provided with openings, cushions extending beneath and in engagement with the rail bases and located between said rail bases and said clamping plates, anchor rods extending through the openings in said clamping plates and having heads seated therein and maintained against upward movement relatively to said plates by said 100 cushions, said anchor rods having their free portions embedded in said sleepers, reinforcing bars embedded in said sleepers and extending lengthwise throughout the same and connected with said anchor rods, 110 and cross-reinforcing bars embedded in said cross-braces and extending lengthwise thereof from the reinforcing bars in one sleeper to the reinforcing bars in the other sleeper.

In testimony whereof I have hereunto set 115 my hand in the presence of two subscribing witnesses.
